J. M. COON

ABDOMINAL SUPPORTER

Filed June 25, 1923

Fig. 1.

—FIG. 2.

Fig. 3.

Fig. 4.

A technical drawing of a cable assembly. The assembly consists of a central core with two outer jackets. The left jacket is labeled with measurements: 16, 2.5, 18, 2.4, 2.7, and 2.6. The right jacket is labeled with measurements: 16, 2.5, 2.4, and 18. A vertical dimension line indicates a height of 2.5. The drawing is signed "Inventor J.M. Coon" at the top right. At the bottom left, it is signed "Witness C. Wagner" and "By Rob. Robins Hil Attorney".

UNITED STATES PATENT OFFICE.

JENNIE M. COON, OF BATTLE CREEK, MICHIGAN.

ABDOMINAL SUPPORTER.

Application filed June 25, 1923. Serial No. 647,693.

This invention relates to an abdominal supporter, and particularly to a garment provided with means for its adjustment to comfortably fit the wearer and retain its position when in use.

The frequent objection to supporters of this character is that they alter their position in the movement of the wearer and are thus rendered uncomfortable and fail to perform their intended functions. There is also a tendency of the front and back pads to roll or fold at the top and bottom edges, which prevents a smooth fit at the waist line and beneath the abdomen.

15 The invention has for an object to provide a novel and improved construction comprising a segmental front pad or piece having vertical braces disposed to retain the general shape of the pad and yieldable laterally 20 to conform to the curvature of the abdomen, together with a similarly braced back pad connected thereto by adjustable straps.

Another object of the invention is to present a special arrangement of the straps connecting the front and back pads by which the waist line strap is adjusted at opposite sides of the front pad and the lower straps adjustable at the sides of the back pad, all of the parts being formed of non-elastic material which preserves the shape and size 30 while materially extending the period of use.

Other and further objects and advantages of the invention will be hereinafter set forth 35 and the novel features thereof defined by the appended claim.

In the drawing:—

Figure 1 is a perspective of the invention;

Figure 2 is a plan view with the parts in 40 extended position;

Figure 3 is an enlarged detail section on line 3—3 of Figure 2; and

Figure 4 is a similar view on the line 4—4 of Figure 2.

45 Like numerals refer to like parts on the several figures of the drawing.

The numeral 10 designates the front pad of the supporter which if desired may comprise two segmental members connected by 50 detachable fastenings 11 at the front of the garment. The position of these fastenings, however, may be changed as found desirable, and particularly if the opening be located at one side of the front. This front pad is connected to a rear pad 12 by means of a series 55 of adjustable straps comprising a waist line

strap 13 secured to the rear pad at 14 and adjustably connected by a slip buckle 15 attached to the front pad. The front ends of the straps 13 are thus disposed at the sides 60 of the front pad and by a rearward draft upon the opposite sides the waist straps may be jointly adjusted so as to properly position the device with an even tension at opposite sides. Beneath the waist strap lower 65 straps 16 are provided, these being secured at 17 to the front pad and extended through slip buckles 18 secured to the rear pad so that the free ends of the straps 16 extend toward the front and can be conveniently 70 grasped by the hand of the wearer to secure an equal adjustment of the straps.

In order to prevent the rolling or overturning of the edges of the pads and also to retain their proper shape while permitting 75 adjustment to the curvature of the abdomen, the pads are provided with bracing means such as indicated at 19 and 20 upon the front pad and at 21 upon the rear pad, these means extending between the upper and lower 80 edges of the pad pieces. It will be noted that the brace 19 extends in a vertical line parallel to the opening between the front pad sections while the brace 20 extends at an angle thereto, leaving an unbraced portion 85 22 which permits the proper fitting of the upper edge of the supporter while the lower edge thereof is stiffened by the approach of the braces to each other, as at 23. Such construction provides the maximum of support 90 beneath the abdomen and permits a proper curvature at the waist line.

While these braces may be applied in any desired manner, still it is often preferable to form the pads of two layers of material, as 95 indicated in Figures 3 and 4, these being connected by lines of stitching 24 extending from the top to the bottom thereof and thus forming a pocket to receive the brace 25. While the form of buckle 18 does not form 100 any part of this invention, still a desirable construction thereof for the purpose of permitting the simultaneous adjustment of the straps, comprises the frame 26 having the gripping bar 27 slidable thereon, as usual in 105 this class of buckles.

The front pad may be of the general configuration herein shown, and for the purpose of securing a comfortable fit leaving the hips 110 free the side edges are curved as at 28 thus comprising a segmental structure while the top edge 29 is substantially straight to fit the

waist line. The rear pad 12 is of a general oval shape adapted to comfortably fit at the small of the back and comprises the straight upper edge 30 and curved side edges 31 merging into a substantially straight lower edge 32.

While the details of construction and configuration have been specifically described, the invention is not confined thereto as 10 changes and alterations may be made in the shape, size and detail construction of the parts.

Having thus described my invention, what I claim as new and desire to secure by Letters Patent, is:

A three piece abdominal supporter com-

prising a front pad composed of substantially segmental parts shaped to fit the curvature of the abdomen and connected by a detachable fastening, a stayed rear pad of less 20 area than the front pad and increasing in diameter downward to fit the lower portion of the back adjacent the base of the spinal column, connecting straps disposed at the upper edges of the front and rear pads, lower 25 connecting straps extending upward from the lower portion of the front pad to the rear pad, and adjusting devices for upper straps at the front pad and for the lower 30 straps at the rear pad.

In testimony whereof I affix my signature.

Mrs. JENNIE M. COON.
